CARROLL L. RIKER, JR., OF NEW YORK, N. Y.

CLOTHES-LINE SUPPORT.

1,103,083.

Specification of Letters Patent. Patented July 14, 1914.

Application filed September 4, 1913. Serial No. 788,046.

To all whom it may concern:

Be it known that I, CARROLL L. RIKER, Jr., a citizen of the United States, residing in New York city, in the county of New York and State of New York, have invented certain new and useful Improvements in Clothes-Line Supports, of which the following is a specification.

The objects of my invention are to provide a swiveled house-bracket for endless clothes lines such that the user does not have to lean out to hang or taken in clothes, or to clear the line when it has been tangled by winds; that the line can run perpendicular, parallel or at any angle from the house-wall; that is at once cheap, simple, light and strong, without loose or delicate parts, easily worked, and adapted to be applied, without change of any of its parts, to windows and doors in frame and masonry buildings and to window and door frames of any type, without danger of splitting their stiles, sills or other members.

In the drawings, Figure 1 is a perspective view showing my bracket applied to a window and swung inwardly with the line perpendicular to the wall; Fig. 2 is a like view with the bracket swung down, to allow the window to be closed; Fig. 3 is a detail view showing the mode of attaching the frame bar to the window frame; Fig. 4 is a top view; Fig. 5 is a side view of the pulley arm; and, Fig. 6 is a section thereof in the line 6—6 of Fig. 5.

My bracket comprises three members, namely, a frame 1, adapted to be secured in any window or door opening and to be at once support and pivot; a stock, 2, swiveled and adapted to be both axially and angularly fixed on the frame 1 and an arm 3, swiveled, and adapted to be fixed upon the stock 2 by the pull of the line 7.

The frame 1 may be made of welded or drawn pipe or tubing. Where there are a great many buildings with windows or doors all of the same clear height I prefer to make the frame 1 J-shaped and attach it by both its stems 11 (Fig. 1), but where the openings run irregular or their details are not standardized, I make the frame 1 L-shaped and attach it by the stem and bar, 12, (Fig. 2). I drill holes, 13, at right angles to one another and preferably (but not necessarily) staggered, in the stem or stems 11 and bar 12; in the former for screwing or bailing it to the window or door frame; in

the latter, in J shaped frames, to serve as pin-holes by which the stock 2 can be pinned fast to the bar 11, at any height and at any angle; and in L-shaped, for the same purpose and also to serve as nail or screw holes by which the bar also can be fastened to the window or door frame, being suitably spaced therefrom by suitable washers.

By drilling the screw holes 13 at right angles, I adapt the frame 1 to be fastened upon the faces of the sill 4, the soffit of the cap and the face of the stile 5, as illustrated in Figs. 1 and 2, which is the readiest mode when the window frame is substantial. When the frame is made of light boards it is preferable to lay the frame 1 in the reveal and fasten it to the edges of the sill and cap and to reveal or reveal molding with screws perpendicular to the plane of the wall and driven into the edges of the frame-members, so as not to split them, as illustrated in Fig. 3.

The stock 2 is made with a swivel head, 21, containing a guide bore by which it is swiveled on the bar 12 of the frame 1 and drilled with pin holes 23 by which it can be pinned thereto; and a (preferably square) prismatic shank 22 at right angles with the swivel head and terminating in a stop 24, which retains the arm 3 on said shank. The arm 3 is preferably cast in H-section, to give strength with lightness, and has an offset eye, 31, at its free end, for mounting a pulley-block, 6, and at its swivel end a mutilated, or engagement-release socket 32, by which it is swiveled on and fixed on the stock shank 22; and adjacent thereto a hook, 38, preferably two-pronged, for the bights of the clothes-line. The mutilated socket 32 is shaped as illustrated to the end that the user, by a simple motion, can change the location of the arm 3 from inboard and horizontal (Fig. 1) to outboard and vertical (Fig. 2), and that when in either of said positions the pull of the line will there retain and hold the arm, strained and free from rattling. In the following description "axial" means lengthwise of the bar, "posterior" toward its socket end, "anterior" toward its free end, and "length" applied to the socket faces, means, direction perpendicular to their intersections.

The socket 32 is formed with adjacent axial and posterior engaging faces 33 and 34, the length of the former being substantially

equal to, and of the latter about one-third of the width of the stock shank 22; an anterior relief-recess 35, adjacent to the axial face 33 and whose length equals about two-thirds to three-quarters said width; an anterior engaging face 36, whose length nearly equals said width; and a nearly semi-cylindrical relief-recess, whose surface 37 extends perpendicularly from the anterior engaging face 36, curves toward but beyond the posterior face 34 and recures thereto.

In the practice of my invention the L-shaped or $\square$ -shaped frame 1 with the stock 2 upon its bar 12 is secured in a door or 15 window opening and made fast to the frame; or to the wall itself, if desired, the bar 12 being suitably spaced by washers to allow for the stock head; the stock 2 is adjusted at the desired height and pinned fast, 20 the socket 32 of the arm 3 is slipped over the finger 24 and onto the shank 22 of the stock 2; and prevented from being shaken off by said finger; and a pulley block 6 through which an endless line 7 has been 25 rove, is hooked into the eye 31 of the arm 3. If now the arm be pulled inboard and lifted to horizontal the equal pulls, $o-p$, $o-p$ of the line as illustrated in diagram in Fig. 5, give the resultant pull $e-f$ on the eye 31, 30 which is resoluble into a force $e-h$ parallel with the arm 3 and a downward force $e-d$ applied to the eye. The force $e-h$ pushes the upper edge of the anterior engaging socket face 36 against the stock shank 22 35 which becomes the fulcrum about which the force $e-d$ acts and pulls the axial and posterior faces 38 and 34 into contact with upper and posterior faces of said shank and into equilibrium of the pressures and reactions exerted between the said engaging and shank faces; with the result that the arm 3 is immovable until the user changes its position. After the line is full of clothes the user picks up the bights of the line, hooks 40 them over the hook 38, takes hold of the inboard end of the arm 3; disturbs the equilibrium of forces by either lifting or wiggling said arm, and having thus released it from the stock-shank 22, swings it down to and 45 stops it in a vertical position. Obviously, this motion shortens the span of the line 7 a trifle, equal to the posterior motion of the hook 38. If the arm be carried past the vertical it swings freely on the shank 22, as 50 shown in Fig. 2. If the arm be stopped when it is vertical, the engaging faces of its socket immediately engages the faces of the shank 22 and its position is thereby fixed and so remains until it is disengaged by an 55 extraneous force. When so fixed as illustrated in dotted lines, Fig. 5; the pulls of the line between the eye 31 and hook 38 are in equilibrium and neutralize each other and the only active forces are the pulls of the 60 spans of line on the hook 38, $o'-p'$, $o'-p'$, 65

whose resultant $e'-f'$, is resoluble into horizontal and vertical forces respectively, $e'-h'$, $e'-d'$. The latter pulls the face 34 into engagement with the upper face and the former pulls the axial face 33 into engagement with inboard face of the shank, whose upper inboard corner may be considered a fulcrum about which the horizontal force $e'-h'$ acts, and because it is more than double the downward force $e'-d'$, tends to rotate the arm outwardly about 70 said fulcrum and to lift the hooks 38 and upwardly force and press the inboard portion of the face 36 firmly against the under fall of the shank 22, and fix the position of the 75 arm 3.

Obviously, wind is the recurring extraneous force other than the hand of the user; and wind can only deflect the line sidewise and increase both its primary pull and the 80 horizontal component thereof on the arm 3 (by lifting the line and decreasing its angle of declination with the arm) and cannot so materially alter the ratios of the horizontal and downward force component as to disengage the arm and cause it to swing freely on the shank; and this is true whether the arm be horizontal or vertical. Therefore the arm will not rattle on the shank. It will be observed that the out-bent stems 11 of the 85 frame 1, by which it is screwed to the sill or cap, or both, is somewhat longer than the shank 22 and that consequently the pull of the line is applied between the screws 8, which fasten the stem 11 and those 9 which 90 fasten the bar 12, and there can be no twisting moment on either, and the stress is divided between them; and this relation is not altered by the fact that the stress is transmitted to them by torsion and bending 95 strains in the bar 12.

I claim as new and desire to protect by Letters Patent:—

1. A swivel bracket for endless lines comprising a frame formed of a swiveling bar 110 and an attachment stem substantially at right angles to one another and adapted to be attached to a structure in an opening through a wall thereof; a stock swiveled and adapted to be fixed on said frame and a 115 polygonal shank thereof substantially perpendicular thereto; and an arm swiveled on said shank; said arm being formed with a mutilated socket adapted to be engaged with said shank when said arm is horizontal and 120 when it is vertical and to be fixed in such engagements by stress in the line.

2. A swivel bracket for endless lines comprising a frame formed of a swiveling bar and attachment stems substantially at right 125 angles to said bar and adapted to be attached to a structure in an opening through a wall thereof, a stock swiveled and adapted to be fixed on said bar, a polygonal shank thereof substantially perpendicular thereto,

an arm swiveled on said shank; said arm being formed with a mutilated socket adapted to be engaged with said shank when said arm is horizontal and when it is vertical, 5 and to be fixed in such engagements by stress in the line.

3. A swivel bracket for endless lines comprising a frame formed of a swiveling bar and an attachment stem substantially at 10 right angles to one another and adapted to be attached to a structure in an opening through a wall thereof, a stock swiveled and adapted to be fixed on said frame, a polygonal shank thereof substantially perpendicular thereto, a terminal stop on said shank and an arm swiveled on said shank; said arm being formed with a mutilated socket adapted to be engaged with said shank when said arm is horizontal and when it is 15 vertical, and to be fixed in such engagements by stress in the line.

4. A swivel bracket for endless lines comprising a frame formed of a bent tube with holes therethrough, a stock swiveled on and 20 adapted to be pinned to said frame and a polygonal shank thereof substantially perpendicular thereto, an arm swiveled on said shank; said arm being formed with a mutilated socket adapted to be engaged with said 25 shank when said arm is horizontal and when it is vertical, and to be fixed in such engagements by stress in the line.

5. A swivel bracket for endless lines comprising a frame formed of a bent tube with 30 series of holes at right angles to one another therethrough, a stock swiveled on and adapted to be pinned to said frame and a polygonal shank thereof substantially perpendicular thereto, a terminal stop on said 35 shank, an arm swiveled on said shank; said arm being formed with a mutilated socket adapted to be engaged with said shank when said arm is horizontal and when it is vertical and to be fixed in such engagements 40 by stress in the line.

6. In a swivel bracket for endless lines, a swivel stock, a square shank thereon, an arm adapted for the attachment of a line and to be swiveled on and angularly fixed by engagement with said shank; said arm being 50 formed with a mutilated swiveling and angularly-fixing socket comprising an axially-extending face whose length substantially equals the shank width, a face extending perpendicularly therefrom somewhat less than the shank-width, a disengagement recess being formed opposite said second named face and extending from said axial face somewhat less than the shank-width, a face extending from said recess, 55 perpendicular to said axial face, substantially a shank-width, and a substantially semi-cylindrical disengagement recess being formed whose surface curves from the last named face beyond and recures to the second-named face.

7. In a swivel bracket for endless lines, a square shank and an arm adapted for the attachment of a line and to be swiveled on and angularly fixed by engagement with 70 said shank; said arm being formed with a mutilated swiveling and angularly-fixing socket comprising an axially-extending face whose length substantially equals the shank width, a face extending perpendicularly 75 therefrom somewhat less than the shank-width, a disengagement recess being formed opposite said second named face and extending from said axial face somewhat less than the shank-width, a face extending from said recess, 80 perpendicular to said axial face, substantially a shank-width, and a substantially semi-cylindrical disengagement recess being formed whose surface curves from the last named face beyond and re- 85 curves to the second-named face.
